UNITED STATES PATENT OFFICE.

HENRY J. PLANT, OF ROCHESTER, NEW YORK, ASSIGNOR TO DEFIANCE CHECK WRITER CORPORATION, OF ROCHESTER, NEW YORK, A CORPORATION.

CHECK-PROTECTOR.

1,352,689.

Specification of Letters Patent. Patented Sept. 14, 1920.

Application filed February 15, 1917. Serial No. 148,781.

To all whom it may concern:

Be it known that I, HENRY J. PLANT, a citizen of the United States, and resident of Rochester, in the county of Monroe and State of New York, have invented certain new and useful Improvements in Check-Protectors, of which the following is a specification.

The present invention relates to check protectors and more particularly to the type in which matter is printed on the check to define an amount beyond which the check is not payable, an object of this invention being to provide a construction which may be manufactured at a minimum cost, the machine work and other expensive operations being reduced to a minimum.

To this and other ends the invention consists of certain parts and combinations of parts, all of which will be hereinafter described, the novel features being pointed out in the appended claims.

In the drawings:

Figure 1 is a plan view of a machine constructed in accordance with this invention;

Fig. 2 is a vertical section on the line 2—2,

Fig. 1;

Fig. 3 is a vertical section on the line 3—3,

Fig. 1;

Fig. 4 is a section on the line 4—4, Fig. 3;

Fig. 5 is a plan view of the bottom plate removed from the machine;

Fig. 6 is a section on the line 6—6, Fig. 1;

Fig. 7 is an enlarged sectional view

35 through the ink roller;

Fig. 8 is a transverse sectional view through the ink roller, showing the manner of applying an end disk or plate; and

Fig. 9 is a detail view of the end of the 40 shaft on which the thumb wheel is secured.

Referring more particularly to the drawings, 1 indicates a casing or housing stamped from one piece of metal to provide a front, a back, a top wall and side walls. The bottom wall 2 is formed by a separate piece and is removable from the casing 1. In this instance, the bottom wall 2 has one edge bent upon itself at 3 and thence upwardly and inwardly at 4 to provide a flange to operate with the inner face of the inclined front wall of the casing, being held to said front wall by a lip or tongue 5 struck up from the flange 4 and passing into a slit or opening 6 in the front wall of the casing. The

rear edge of the bottom 2 carries a spring 55 tongue 7, having a deflected free end 8 and extending upwardly from a portion 9 which is bent upon the bottom plate 2. This tongue 7 also has a projection 10 struck up therefrom and adapted to enter an opening 11 in the rear wall of the casing 1. On opposite sides of the spring tongue 8, the bottom 2 is provided with upwardly-extending flanges 12 which project from the inner edges of the portion 13 bent upon the bottom plate 2. 65

Within the casing 1, the printing member 14 is arranged, this member being in the form of a drum or wheel having lines of type 15 thereon extending in the direction of the axis of the wheel. The printing 70 wheel is preferably hollow in form with radial blades 16 connecting the outer portion of the wheel with the hub or sleeve 17 one end of said sleeve projecting beyond the drum at 18 to coöperate with an inner side 75 wall of the casing 1, and the other end of the drum being inclosed by a wall 19 from which projects a gear wheel 20 integral with said wall, said gear wheel having a projecting hub 21 for coöoperating with an end wall 80 of the casing 1. A shaft or spindle 22 extends through the sleeve 17 and is journaled in the end walls of the casing being held against movement by a key or pin 23. One end of this shaft is provided with an annular 85 groove 24 and this grooved end has a thumb wheel 25 formed of a plastic material and molded on said end, the shaft or spindle being flattened at 26 to prevent the turning of the thumb wheel 25 thereon. 90

Upon one end of the printing wheel 14 a smooth cylindrical surface 27 is formed and this surface is cut to form numbers 28 which are arranged opposite to the lines of type 15 to provide a dial to indicate the matter 95 that would be printed by the line of type. To the end that these members, and also the lines of type, may be exposed, the casing is provided in its top wall with a slot 29, one end of which is enlarged at 30, the enlarged 100 portion exposing the characters 28 and the slot exposing the lines of type. An integral projection 31 may extend from the end wall of the opening 30 to point out the character 28 which is to be printed. 105

The work is placed upside down upon the top wall of the casing which therefore acts as a work support, and this work is pressed

against the printing line by a platen 32 in the form of a strip of steel with a serrated face 33, the serrations in this instance being in the form of pin points which enter into 5 pockets formed in type faces in a manner well known in this art. In this instance, the platen is carried by a lever 34 in the form of a die casting in which the platen 32 is partially embedded. From the rear end of this 10 lever, two projections 35 extend downwardly and are mounted to turn upon a rod 36, said rod being secured at opposite ends in the side walls of the casing, the top wall of the casing having openings 37 through which the 15 projections 35 depend, and the rear walls of these openings contacting with the arms or projections 35, and serving as stops to limit the upward movement of the platen 32. A spring 38 is coiled about the rod 36 and has 20 one end 39 bearing against the rear wall of the casing, and the other end 40 connecting with one of the depending arms 35. This spring acts on the lever 34 to move the platen 32 away from the type wheel after an impression has been made.

The centering wheel 20 hereinbefore referred to is engaged by a centering device which, in this instance, is in the form of an arm 41 mounted to turn on the rod 36 30 at one end, and having at its free or forward end a laterally-turned portion 42 which projects upwardly above and downwardly below the arm 41. The downwardly-extending portion coöperates with the center of the wheel 20, while the upwardly-extending portion projects into the slot 29 and is adapted to be engaged by the platen 32 when the latter is moved to coöperate with the printing wheel. This action tends to 35 prevent the shifting of the printing wheel while the platen is coöperating with such wheel. A spring 43 surrounds the rod 36 and has one end coöperating with the top wall of the casing as at 44, while the other 40 end 45 coöperates with the laterally-turned portion of the pawl 41. By this arrangement, the pawl is yieldingly held in co-operation with the centering wheel 20 and permits the rotation of the latter in either 45 direction.

The inking of the printing wheel may be effected by an inking roller preferably mounted on the bottom wall 2 of the casing. In this instance this inking roller comprises 50 a spindle 46 surrounded by felt or other absorbent material, preferably in the form of perforated disks 47 abutting retaining plates 48 at opposite ends thereover. Each of these retaining plates may have a central opening 49 with a passageway 50 leading therefrom to one edge of the plate, the inner end of the passageway being narrower than the diameter of the opening 49. At each end 55 of the spindle 46 two annular grooves 51 and 52 are arranged, the spindle 46 at the

groove 51 being of a diameter substantially equal to the width of the inner end of the passageway 50, whereas the spindle at the groove 52 has a diameter substantially equal to the diameter of the opening 49, the groove 52 being situated nearer the adjacent end of the spindle than is the groove 51. By this arrangement, the absorbent material 47, when compressed in the direction of the length of the roller, permits each retaining 70 plate or disk 48 to move in its plane in the groove 51, as shown in Fig. 8, until said disk or plate is centered with reference to the spindle 49, after which the absorbent material 47 expands and forces the disk or 80 plate 48 into the groove 52 where it is held against removal in the direction of the plane, owing to the fact that the spindle at the groove 52 is greater in diameter than the width of the inner end of the passage- 85 way 50.

The spindle 46 of the inking roller is preferably guided in the slots 53 in two upstanding projections or supports 54, which are cut from the bottom plate 2 in the manner shown in Fig. 5. These slots permit the roller to adapt itself to the surface of the printing wheel, and the roller is held toward the latter by spring arms 55 secured to the opposed faces of the supports by portions 56 struck up from the support, the free ends of the arms engaging the spindle 46 on the under side of the latter between the supports and the ends of the rollers so as to be sustained against lateral displacement. 100

The operation of the invention is as follows: The printing wheel 14 is turned by the thumb-piece 25 to present any desired line of type 15 to the printing opening 29, the indications 28 being employed for determining the line to be printed. During the rotation of the printing wheel, the inking roller travels over the faces of type to coat the latter with ink. After the desired line has been placed in printing position, 105 the work is placed in an inverted position on top of the casing 1, and the platen lever 34 is depressed to bring the platen 33 into contact with the work to force the latter through the opening 29 into contact with 110 the printing type line. With the release of pressure on the platen 34 the spring 38 swings the platen 33 upwardly. 115

According to this invention, the platen carrying lever is pivoted within the casing 120 below the top of the casing so that the side walls of the casing may be used as the support for the pivot rod. This rod also serves to support the centering pawl which is so formed that it may be made from sheet material of a minimum thickness. The ink roller is mounted in an inexpensive and durable manner and is constructed with the purpose in view of reducing the manufacturing cost of the machine. 125 130

What I claim as my invention and desire to secure by Letters Patent is:

1. In combination with a work support, a rotary printing wheel, a centering wheel turning with the rotary printing wheel, a platen for coöperation with said printing wheel, a platen carrying lever, a rod on which said lever turns, and a pawl mounted to turn on said rod to coöperate with said centering wheel.
2. In combination with a work support, a printing wheel arranged beneath said work support, a platen carrying lever operating above said work support about an axis below the plane of said work support, a centering wheel mounted to turn with the printing wheel beneath said work support, and a centering pawl mounted to turn about the axis

of the platen carrying lever and coöperating with the centering wheel.

3. In combination with a printing wheel and a pivotally mounted lever carrying a platen for coöperating with the printing wheel, and a pivoted centering pawl mounted to turn about the axis of the platen carrying lever.

4. In combination with a printing member, and a centering wheel turning therewith, a pivoted centering pawl formed from sheet material and having a laterally turned portion at its free end for coöperating with the centering wheel, and a platen for coöperating with said laterally turned portion and with said printing member.

HENRY J. PLANT.
